PAUL BUNET, OF MOISSY-CRAMAYEL, FRANCE.

HIGH-TENSION ELECTRICAL CONDENSER.

Application filed April 14, 1921. Serial No. 461,247.

To all whom it may concern:

Be it known that I, PAUL BUNET, a citizen of the French Republic, and a resident of Rue Mauloy, Moissy-Cramayel, Department 5 of Seine-et-Marne, France, have invented new and useful Improvements in High-Tension Electrical Condensers, of which the following is a specification:

This invention relates to high-tension 10 electrical condensers.

In the construction of electrical condensers for high tensions, a difficulty is experienced arising from the influence of the edges of the electrodes which are arranged 15 to face one another. For the electrical density increases considerably as the edges of the electrodes are approached, and upon the actual edges it assumes a very high value if these edges are thin or cut to sharp angles. 20 The disruptive tension, at which the breakdown or piercing of the dielectric takes place, decreases with an increase of this density, so that the condensers can only be used for a working voltage which is much lower 25 than that which corresponds to the thickness of the dielectric in the central part of the electrodes, and even under these conditions it always presents at its edges weak points which may bring about its destruction.

The present invention has for its object to remedy the disadvantage of this considerable increase of the electrical density at the edges, by constructing the electrodes in such a way that it is possible to regulate this 35 density according to a suitable law. For this purpose, instead of employing a surface formed of simple plates or sheets, the surface is constituted at least in part by means of solid or hollow round bars, rods or tubes, 40 of diameter proportional to the dimensions of the apparatus; in general the most advantageous diameter lies between the third and the tenth part of the distance between the plates. These rods or bars need not be placed along one another, because the capacity 45 is not greatly affected by leaving a certain gap between them. But when this separating gap is increased beyond a certain limit, the capacity begins to diminish rapidly with the separation. This limit varies with the distance between electrodes, and for small distances it is a considerable fraction of this actual distance. As the edges of the 50 plates are approached, the distance between the bars of the same electrode will be increased, so that the capacity per unit of sur-

face remains within a fixed limit. In this way the electrical density will not increase dangerously at the edges of the condenser.

This arrangement can be carried out the 60 more effectually since it is possible to increase the diameter of the terminal or outermost bars, at the same time increasing the interval between these bars and those of the adjacent electrodes. It is sufficient for this 65 purpose to regulate the intervals between successive bars in a suitable way, as represented upon the appended drawing.

Instead of employing electrodes formed entirely of bars or rods, the centre of the 70 electrodes may comprise flat surfaces such as a sheet of metal, with bars only at the edges, their number being greater or less according to the value of the electrical density which it is desired to have at the edges. 75

From the practical point of view, there may be adopted circular electrodes formed of a spiral made up of one or more rods or bars, of which the edge rings or outer coils separate from the inner portion, and the 80 outermost coil closes upon its circumference or not, as desired. There may also be employed square or rectangular electrodes, the angles or corners being suitably rounded. As already stated, the centre may, or may 85 not be, formed by a plane surface.

Another advantageous arrangement is that formed by concentric cylinders, in which case there are only the two extreme edges of the cylinders to be provided with 90 means for limiting the electrical density. The cylinders may be composed of successive tubular rings stacked upon one another with increasing gaps at their edges, or else a kind of helix with increasing pitch as the edges 95 are approached. As in other cases, the centre portion may be formed of sheet metal coiled into a cylinder, the tubes being employed only towards the edges.

The accompanying drawings illustrate 100 more or less diagrammatically a construction in which the invention is embodied in one form, Fig. 1 being a partial vertical section, and Fig. 2 being a corresponding partial side elevation. As here illustrated, 105 each electrode comprises a central cylindrical plate *a* formed by the walls *a*¹ and *a*² soldered together and bounded by a tube *g* carefully soldered to the central plate, for example by tin, and in such manner as to avoid 110 sharp angles. Spaced from this central plate and from each other are arranged tubes

c in the form of rings which are connected together by bridges *d* constructed in such manner as to avoid surfaces of short radius of curvature or sharp corners. The distance between the electrodes is determined by the blocks *e* of insulating material, arranged at suitable intervals. The diameter of the tube *c* is predetermined with respect to the dimensions of the apparatus. In general the most advantageous diameter lies between $\frac{1}{3}$ to $\frac{1}{6}$ of the distance between the electrodes. The spacing between the adjacent tubes *c* of the same electrode increases toward the margin of the electrodes, but the spacing is unequal for the tubes of adjacent electrodes of the condenser as indicated in Fig. 1, in such manner that the interval between the tubes of the electrodes increases as they approach the margins of the electrodes. In this fashion the electrical density does not dangerously increase at the margins. For this purpose also it is possible to increase the diameter of the tubes arranged at the margin of the electrodes.

The whole of the condenser will be placed in a tank or other vessel into which an insulating liquid such as oil will be introduced; certain vegetable oils are quite suitable for this purpose, having a considerable electrical rigidity greater than 70,000 volts per centimetre and a high specific capacity reaching to $4\frac{1}{2}$ or 5, as well as a relatively low cost.

Instead of liquids, there may be introduced a plastic material or a solid such as paraffin wax.

In order to avoid accidents, if foreign substances are found floating in the liquid, there may be provided barriers *f* made of cardboard or like material.

It will be understood that the invention is not limited to the forms of construction which have been described; thus the arrangement of the rods or tubes, their conformation and number may be varied within wide limits, in certain particularly simple cases there may be used only the central plate *a* and a single tube *g*.

The plates may be formed not only by means of solid or apertured metal sheets, but also in whole or in part from substances such as paper, cardboard, wood or other, coated with metal or rendered conductive of electricity.

The plates of the condensers according to this invention may be connected alternately to the two poles of a source of current, or with triple, quadruple, or other alternation in the case of more than two poles, as for polyphase voltages.

Having now particularly described and ascertained the nature of my said invention and in what manner the same is to be performed, I declare that what I claim is:—

1. A high tension electrical condenser

comprising electrodes separated by a dielectric, each of said electrodes comprising rods of substantially circular cross section permanently electrically connected together so as to prevent sparking between the parts, the distance between successive rods of each electrode at the margin thereof gradually increasing towards the edge of the electrode.

2. A high tension electrical condenser comprising a pair of electrodes separated by a dielectric, each of said electrodes comprising rods of substantially circular cross section, permanently electrically connected together so as to prevent sparking between the parts, the distance between successive rods of each electrode at the margin thereof gradually increasing towards the edge of the electrode, but varying in said electrodes so that the interval between the rods of the different electrodes increases as they approach the margins of the said electrodes.

3. A high tension electrical condenser comprising electrodes separated by a dielectric, each of said electrodes comprising rods of substantially circular cross section, permanently electrically connected together so as to prevent sparking between the parts, the distance between the successive rods of each electrode and the diameter of the different rods of each electrode at the margin thereof gradually increasing towards the edge of the electrode.

4. A high tension electrical condenser comprising electrodes separated by a dielectric, each of said electrodes comprising a central plate with rounded edges, and rods of substantially circular cross section, arranged in extension of the edge of said plate, permanently electrically connected together and with the central plate so as to prevent sparking between the parts, the distance between the successive rods of each electrode at the margin thereof gradually increasing towards the edge of the electrode.

5. A high tension electrical condenser comprising a pair of electrodes separated by a dielectric, each of said electrodes comprising a central plate, with rounded edges, and rods of substantially circular cross section, arranged in extension of the edge of said plate, permanently electrically connected together and with the central plate so as to prevent sparking between the parts, the distance between the successive rods of each electrode at the margin thereof gradually increasing towards the edge of the electrode, but varying in said electrodes so that the interval between the rods of the different electrodes increases as they approach the margin of the said electrodes.

6. A high tension electrical condenser comprising electrodes separated by a dielectric, each of said electrodes comprising a central plate with rounded edges, and rods of substantially circular cross section, ar-

- ranged in extension of the edge of said plate, and permanently electrically connected together and with the central plate so as to prevent sparking between the parts, the distance between the successive rods of each electrode, and the diameter of the different rods of each electrode, at the margin thereof gradually increasing towards the edge of the electrode.
10. 7. A high tension electrical condenser comprising electrodes separated by a dielectric, each of said electrodes comprising rods of substantially circular cross section, having the form of rings, permanently electrically connected together so as to prevent sparking between the parts, the distance between the successive rods of each electrode at the margin thereof gradually increasing towards the edge of the electrode.
15. 8. A high tension electrical condenser comprising electrodes separated by a dielectric, each of said electrodes comprising rods of substantially circular cross section, having the form of rings permanently electrically connected together so as to prevent sparking between the parts, the distance between the successive rods of each electrode at the margin thereof gradually increasing towards the edge of the electrode, but varying in said electrodes so that the interval between the rods of the different electrodes increases as they approach the margins of the said electrodes.
20. 9. A high tension electrical condenser comprising electrodes separated by a dielectric, each of said electrodes comprising rods of substantially circular cross section, having the form of rings permanently electrically connected together so as to prevent sparking between the parts, the distance between the successive rods of each electrode and the diameter of the different rods of each electrode at the margin thereof gradually increasing towards the edge of the electrode.
25. 10. A high tension electrical condenser comprising electrodes separated by a dielectric, each of said electrodes comprising a cylindrical plate with rounded edges, and ring-like rods of substantially circular cross section, arranged coaxially with and in extension of the edge of said plate, and permanently electrically connected together and with the central plate so as to prevent sparking between the parts, the distance between the successive rods of each electrode at the margin thereof gradually increasing towards the edge of the electrode.
30. 11. A high tension electrical condenser comprising electrodes separated by a dielectric, each of said electrodes comprising a cylindrical plate with rounded edges, and ring-like rods of substantially circular cross section, arranged coaxially with and in extension of the edge of said plate, and permanently electrically connected together and with the central plate so as to prevent sparking between the parts, the distance between the successive rods of each electrode at the margin thereof gradually increasing towards the edge of the electrode, but varying in said electrodes so that the interval between the rods of the different electrodes increases as they approach the margins of the said electrodes.
35. 12. A high tension electrical condenser comprising electrodes separated by a dielectric, each of said electrodes comprising a cylindrical plate with rounded edges, and ring-like rods of substantially circular cross section, arranged in extension of the edge of said plate, and permanently electrically connected together and with the central plate so as to prevent sparking between the parts, the distance between the successive rods of each electrode and the diameter of the different rods of each electrode at the margin thereof gradually increasing towards the edge of the electrode.

In testimony whereof I have signed my name to this specification.

PAUL BUNET.
